UNITED STATES PATENT OFFICE

ISAAC V. TRULLINGER, OF MULINO, OREGON

LOG TURNER FOR SAWMILLS

Application filed July 10, 1929. Serial No. 377,199.

This invention relates to log handling devices and has for an object the provision of means which may be positioned between the head blocks of a mill carriage to load logs

5 therein so that the latter may be acted upon by the saw, the construction being such that the log may be canted or turned to present a different face to saw.

Another object of the invention is the provision of a log canting gear of novel construction, which may be readily operated to load and turn logs and which provides a mechanism for the above purpose that is positive and reliable in construction and operation, 15 and may be easily applied to a mill carriage.

With the above and other objects in view, the invention further includes the following novel features and details of construction, to be hereinafter more fully described, illustrated in the accompanying drawings and 20 pointed out in the appended claims.

In the drawings:—

Figure 1 is a top plan view showing a portion of a mill carriage with the invention applied.

Figure 2 is a sectional view on the line 2—2 of Figure 1 with the mechanism shown in loading position.

Figure 3 is a section on the line 3—3 of 30 Figure 1 with the log turning position of the mechanism shown by dotted lines.

Figure 4 is a detail perspective view of the operating bar.

Figure 5 is a sectional view on the line 35 5—5 of Figure 3.

Figure 6 is a fragmentary longitudinal section taken longitudinally through adjacent ends of the arm sections with sections shown in separated relation.

40 Referring to the drawings in detail wherein like characters of reference denote corresponding parts, the reference character 10 indicates parallel sills of a mill carriage which is movably supported upon wheels 11 45 which travel over tracks 12, the carriage being designed to support logs as indicated at 13. The carriage includes spaced head blocks 14 from which rise the usual knees 15.

The log handling mechanism is designed to 50 be positioned between a pair of head blocks

14 and while only one pair is shown, the number of head blocks may be increased, in which case the mechanism will be arranged between adjacent blocks.

Rising from one of the sills 10 are spaced 55 bearings 16 which rotatably support a shaft 17, while rotatable upon this shaft between spaced collars 18 is a sprocket 19. This sprocket is housed within one end of one section 20 of an arm 21, the other section 22 of 60 which is pivotally secured to the section 20 as shown at 23. The sections 20 and 22 of the arm 21 are transversely channel-shaped and the sprocket 19 is housed between the side walls of the section 20 at the inner end 65 of the arm. The shaft 17 passes through the section 20 of the arm 21 so that a housing is provided for the sprocket 19. The section 22 of the arm 21 is provided with a lug 22', and the adjacent end of the section 20 is 70 squared as at 20' to engage this lug and limit relative pivotal movement of the arm sections in one direction.

A sprocket chain 24 passes around the sprocket 19 and around the sprocket 25 at 75 the outer end of the arm, while a guide sprocket 26 is mounted upon the pivot 23 of the arm for engagement by the chain.

The chain 24 carries spaced teeth 27 which are designed to engage the log 13 when the latter is being moved, so that when the arm 21 is positioned as shown in Figure 2 of the drawings, the teeth will rise and engage the log 13 so as to move the latter along the head blocks into contact with the knees 15. 80

In order to effect this operation, the shaft 28 upon which the sprocket 25 is mounted, has pivotally secured thereto the inner end of a leg 29. One of these legs is positioned upon each side of the outer end of the arm 21 90 and their outer ends have mounted between them a grooved wheel 30. The wheel 30 is slidable upon a track 31 arranged below the arm 21 and provided at its outer end with an upwardly inclined or raised portion 32. 95 This track 31 is carried by a beam 33' which connects the sills 10.

Pivotally secured to the lower ends of the legs 29 are the outer bifurcated ends of a bar 33. This bar is illustrated in detail in Fig- 100

ure 4 of the drawings and its intermediate portion is bent as at 34 to provide an offset end 35 having a longitudinally disposed slot 36. This slot receives the shaft 17 and is 5 slidable upon a bushing or collar 37 upon the shaft. The bar 33 may thus be moved longitudinally along the track 31. When the bar is moved outward to cause the roller 30 to ride upward upon the inclined section 32 of the track, the outer end of the arm 21 will 10 be raised to the position shown in Figure 2 of the drawings, which is the log holding position of the mechanism.

When the bar 33 is moved in an opposite direction, or to the position shown by the dotted lines in Figure 3, the sections 20 and 22 of the arm 21 will be moved relatively upon the pivot 23 so that the intermediate portion of the arm 21 will be raised to bring the chain 24 into engagement with the log. Upward movement in this position is limited by stops 38 which extend downward from the adjacent ends of the arm sections 20 and 22, while a roller 39 acts to prevent the chain from dropping at this point. This roller may be suitably grooved to permit of the passage of the teeth 27 of the chain 24.

Various means may be utilized to impart movement to the bar 33, the means shown consisting of a pressure cylinder 41 within which operates a piston (not shown). A rod 42 which is connected to the piston and extends from the cylinder has its outer end suitably connected with the adjacent end of the bar 33.

35 The chain 24 may also be driven from any suitable source, the means shown consisting of a motor 43 which has a pitman connection as shown at 44 with a shaft 45. This shaft has mounted thereon a pinion 46 which engages and drives a gear 47 upon the shaft 17.

40 The invention is susceptible of various changes in its form, proportions and minor details of construction and the right is herein reserved to make such changes as properly fall within the scope of the appended claims.

45 Having described the invention what is claimed is:—

1. In a log canting gear, a sectional arm, means pivotally connecting adjacent ends of 50 said sections, means to pivotally mount one end of the arm, means operatively connected with the other end of said arm to move the end of said arm pivotally upward or to move the arm sections relatively, a log engaging element movable along the arm, and means to move said element.

2. In a log canting gear, a sectional arm, means pivotally connecting adjacent ends 55 of said sections, means to pivotally mount one end of the arm, means operatively connected with the other end of said arm and movable in one direction to move said end upward and in an opposite direction to move the sections 60 upward at their point of pivotal connection, a

log engaging element movable along the arm, and means to move said element.

3. In a log canting gear, a sectional arm, means pivotally connecting adjacent ends of 70 said sections, means to pivotally mount one end of the arm, a track located below the arm, an elevated section at one end of the track, a leg having one end pivotally secured to the other end of the arm and movable along the track, means to force the leg in one direction 75 to engage the elevated section of the track and move the end of the arm pivotally upward, or to move said leg in an opposite direction to force the sections upward at their point of pivotal connection, a log engaging element movable along the arm, and means to move said element.

4. In a log canting gear, a drive shaft, means to operate the shaft, a sectional arm having one end pivotally mounted upon the 85 shaft, means pivotally connecting the arm sections, a track below the arm, an upwardly inclined section in said track, means movably secured to the outer end of the arm and engaging the track to support the end of the 90 arm, a bar having a longitudinally disposed slot in one end to receive the shaft and having its opposite end connected with the leg, whereby the latter may be moved in opposite directions to elevate the outer end, or the intermediate portion of the sectional arm, means to move the bar and movable means carried by the arm and operatively connected with the shaft to engage the log.

In testimony whereof I affix my signature. 100
ISAAC V. TRULLINGER.
